UNITED STATES PATENT OFFICE.

LEE LARSEN, OF TAMPICO, MEXICO.

LOOSE-SHEAVE-SPPOOL ROTARY TABLE.

1,366,571.

Specification of Letters Patent. Patented Jan. 25, 1921.

Application filed June 1, 1920. Serial No. 385,847.

To all whom it may concern:

Be it known that I, LEE LARSEN, a citizen of the United States of America, residing at Tampico, in the State of Tamaulipas, Republic of Mexico, have invented certain new and useful Improvements in Loose-Sheave-Spool Rotary Tables, of which the following is a specification.

My invention relates to rotary boring for screwing in hollow or solid concrete or iron piles and any kind of pipes, as well as funnel shaped piles, pipes or cylinders. Also in such cases where boring through the strata is necessary for sinking pipes for instance in oil fields, my invention will offer great advantages.

The objects of my invention are to secure an exact and safe operation in placing piles, pipes or the like, of any diameter, and to provide means by which is obtained a strong, firm and even hold all around these elements without harming the material to be put down. Means are also provided to permit the couplings or flanges on pipes or the like to slip right through between the spools, in order to secure a continuous operation, so to allow that as many pipes as desired can be connected up at one time and to let them all through until the next set is ready. Furthermore, means are provided so that a quick and easy change of the spools in case of necessity can take place.

In the accompanying drawings, two preferred forms of the invention are illustrated. In these drawings, Figure 1 represents a top view of a four spool turning table, and Fig. 2 is an elevation of the same, partly in section. Fig. 3 is a plan view of a modification of my invention with two loose sheave spools; Fig. 4 is a side elevation of this mechanism, and Fig. 5 is an elevation of the rotary table, showing the spool in position, and also indicating by dotted lines the apparatus open for replacing spools, etc.

In the form of the invention shown in Figs. 1 and 2, the rotary table 1 is provided with four loose sheave spools, each spool being connected to an ordinary turn-table rotary of the same construction as used for drilling purposes, by castings 3 and 4, and located in such a manner that they can grip with the sheaves evenly around on the material to be screwed down. The spools are formed by a certain number of sheaves 2, according to the diameter of the element to be gripped. They can either be made of

metal or wood, but if wooden sheaves are used, a hard wood should be employed, and in all cases a metal sheave should be used on each end of the spool, so as to protect the wooden sheaves from breakage. The sheaves are of various diameters according to the shape and size of the material in operation, and can be faced at any thickness according to the number of sheaves necessary for the purpose. The edges of these sheaves can be provided with furrows 2^a, to give more friction and to get a better hold of the material under work. All the sheaves have grooves 5 as shown in Fig. 2, to allow them to turn independently on the brass pipe 7, which is crimped on both ends, forming a collar 7^a, just sufficient to keep the sheaves together and in place and with enough space to allow them to turn freely. The safety collars or washers 6, which are placed at each end of the spool, are conveniently split in two halves (see Figs. 4 and 5), and held together by stud bolts 6^a, so that they can easily be taken apart and lifted up and put back, when the spools have to be taken off for instance to be changed for other sizes of sheaves, and will also help to keep the sheaves together.

Each spool, thus formed by sheaves of various diameters according to the size and shape of the elements to be screwed down, is placed on a shaft 8 which can rest with its ends in the pedestals 9; these pedestals or bearings can freely travel on large screws 10, located in the fixed iron blocks or castings 3 and 4, in order to adjust the position of the spools. For this purpose the screws 10 are provided with a square head 11 which serves as nut for the double faced wrench 9^a lever 12, which lever after being used for regulating the position of the spools is placed over the nuts 11, thus preventing the screws 10 from turning out of position, but will keep the spools firm up to the element to be screwed down.

The rotary table is turned as usual by means of the cog-wheel 14, which is turned by shaft 13. However, in case a large cylinder has to be screwed in, it would be advisable to use a turn-table with two shafts, as shown in Fig. 1, so as to give more power and equalize the strain on the table 1.

It is evident that by employing these loose spools, the elements to be screwed down can be fixed between the spools in a very strong and even hold by means of the sheaves which

are formed in lines exactly according to the diameter and shape of said element, and the material is now secured from being cracked or damaged, as often has been the case by 5 the former known means for said purpose.

Referring to the small rotary illustrated 10 in Figs. 3 to 5, this apparatus should offer great advantages for instance for sinking pipes in oil fields, as it permits the unions or flanges on the pipes to slip right through between the spools by loosening the springs 22^a so as to give space enough to permit the said unions or flanges to pass through without stopping.

15 In this modified form of my invention the spools formed by the sheaves 2 are placed in the movable pedestals 15 on the shaft 8 in the same manner as described for the four spool rotary, but one end of the shaft can 20 conveniently turn on the pin 16 in order to easily move the shaft up to the position as shown by dotted lines in Fig. 5 for replacing spools if desired or necessary.

The adjustment of the spools can be effected by means of shafting 17 which rests 25 in fixed blocks 18 and runs right through the bearings 15. This shafting 17 is threaded in both ends, right and left, according to the movement required, and by moving the 30 ratchet 19 with its cog-wheels 20 which turn the shafting 17, the iron block 21 placed in the threaded part of the shafting 17 will push up against the springs 22^b thus 35 pressing the spools together until they have gotten a firm and strong hold on the pipe under work. If flanges or unions have to 40 pass the spools, the ratchet is given a little turn and the springs 22^a will permit the spools to open and give sufficient space for this part of the pipe to pass between the 45 spools, and this is continued in the same manner until the entire pipe is put in place.

The Z-shaped irons 23 serve as guides for the pedestals on bearings 15 and the iron blocks 21, so that the operation can be effected in a safe and easy way.

This apparatus as shown in Fig. 3 will grip almost all around the pipe, and will give an even and strong grip which cannot do any damage to the pipe, as the sheaves turn all independently, and there will be no more drag on one than on the others as all the sheaves turn absolutely free, and by the simple mechanism of the 55 springs the apparatus can open and close the spools almost without stopping the machine.

By adopting this loose sheave spool rotary with either two, three or more sets of 60 spools, it will render great utility to any

place where large columns or the like have to be put in, as this apparatus will turn around at a good speed and take a strong, firm and even hold all around the elements, and when first screwed up tight it cannot 65 slip nor do any damage to the element in work, as is the case with the now employed rollers in use at the present, which have been the cause of constant trouble and also many cylinders and pipes have been cracked 70 and damaged causing lots of delay and expense. This apparatus however, will work the element down in a safe manner and absolutely plumb, which will guarantee a good and safe placement of the object to be 75 screwed down.

It is obvious that many changes in the details of construction may be made without departing from the spirit and scope of this invention, and I do not wish to be limited to 80 the details of construction as set forth in this specification.

Having thus described my invention, what I claim as new and desire to secure by Letters Patent is as follows:—

1. In a rotary table for screwing or twisting down concrete or iron piles or pipes to any desired place, loose sheave spools fixed to said table to clutch the element to be twisted or screwed down, said spools comprising sheaves of various diameters to grip and fit said element; a brass pipe, said sheaves being turned with freedom of movement on said pipe; means to adjust the distance between said spools; and guiding 95 means for said spools to and from the said element.

2. A rotary table for screwing or twisting down concrete or iron piles or pipes to any desired place of the class described, as set 100 forth in claim 1, and means for adjustably positioning said loose sheave spools from and toward the element to be twisted or screwed down, for adjusting the distance between said spools.

3. A rotary table for screwing or twisting down concrete or iron piles or pipes to any desired place of the class described, as set forth in claim 1, and means for guiding said loose sheave spools, said guiding means 110 disposed on each side of said spools for effecting the adjustment of the distance between said spools.

In testimony whereof I affix my signature in presence of two witnesses.

LEE LARSEN.
